UNITED STATES PATENT OFFICE.

SYDNEY MARTIN, OF MONTREAL, QUEBEC, CANADA.

GAME.

Application filed May 20, 1922. Serial No. 562,413.

To all whom it may concern:

Be it known that I, SYDNEY MARTIN, a subject of the King of Great Britain, residing at Montreal, Province of Quebec, Canada, have invented certain new and useful Improvements in Games; and I do hereby declare that the following is a full, clear, and exact description of the invention, such as will enable others skilled in the art to 10 which it appertains to make and use the same.

This invention relates to games, and is designed to provide a neat and compact game apparatus as well as an interesting 15 and entertaining game.

A further object of the invention is the provision of a novel score board and score keeping device therefor. Further objects and advantages of the invention will appear 20 as the description continues.

For the purpose of illustration, reference is made to the accompanying drawings in which:

Figure 1 is a perspective view of the game 25 casing;

Figure 2 is a central vertical section there- 30 through;

Figure 3 is a section similar to Figure 2, showing the cover in raised position;

Figure 4 is a face view of the game disk;

Figure 5 is a face view of the score keep- 35 ing disk;

Figure 6 is a fragmentary section through the center post;

Figure 7 is a detail sectional view of the game disk, showing the manner in which a playing object is received therein;

Figure 8 is a detail of the score keeping 40 element; and,

Figure 9 is a similar detail, showing the manner in which said element is received in the score disk.

In the accompanying drawings, the game casing generally designated by the numeral 45 1 consists of a receptacle or body portion 2 provided with a cover 3. These members are connected by means of a hinge 4 one of the levers of which is provided with a stop member 5 for limiting the outward movement of the cover, as clearly shown in Figure 3. The cover is normally held closed by means of a lock which consists of a flat spring 6 having one end secured to the inner wall of the receptacle as at 7, while the 50 free end is provided with a button 8 engageable in an aperture 9 formed through

the side of the cover. A center post 10 having a base 11 is riveted to the body of the receptacle, and has formed therein a recess 12 which constitutes the bearing for a spindle 13. The upper end of the spindle is reduced and threaded as at 14 forming a shoulder 15. The game disk 16 rests on the shoulder and is tightened thereto by means of a knurled nut 17.

The game disk consists of a substantially flat plate which slopes downwardly at an angle of about one half degree from the circle generated around the center of the disk by the point 18. At the periphery of this 70 inclined portion, depressions 19 are formed in the disk, and the latter then slopes upward as at 20 at an angle of about one half degree to the edge of the disk, where there is provided an upwardly inclined flange 21. The face of the disk is divided into sectors 22 by means of the lines 23, each sector including one depression. A numeral and plus or minus sign are indicated adjacent each depression, and designate the value of said 80 depression in a manner later to be explained. A plurality of playing objects, such as balls 24, are adapted for reception in the depressions, and may lie on the bottom of the receptacle when the game is not being played. Each object bears a distinguishing characteristic which may consist of a distinct color. The sectors may also be variegated.

A score board or disk 25 is secured to the inner side of the cover by means of threaded bolts 26, the shanks of which are enclosed by collars 27 for spacing the disk from the cover. The disk is divided into a number of sectors 28 which are formed by radii 29. These sectors are preferably distinguished from one another by colors corresponding to those of the balls 24. In this case, the lines of division between the sectors are produced by the contrast between the distinct colors of the adjacent spaces. Each sector has formed therein an equal number of perforations 30 each one of which bears a value numeral 31. In order to conserve space on the sector and to add interest to the keeping of the score, certain of the apertures are formed in irregular or zig-zag lines as at 32. An additional perforation is formed at the point of intersection 33 of the sectors, this point and perforation being common to all the sectors and being identified by a numeral designating the maximum score that can be made in

any sector. Thus the winner is easily identified as the first player reaching the aperture 33. The initial aperture of each sector is indicated by the word "Start," as shown in 5 Figure 5. The score may be kept by any usual type of peg, but a special and preferable score keeping element is shown in Figures 8 and 9. This consists of an angular wire spring 34 the ends of which are formed 10 with eyes 35, while the vertex is slightly flattened, as at 36. In use, when it is desired to insert one of these elements into an aperture, the eyes 35 are pressed together by the fingers, whereupon the end 36 is practically 15 closed so that it may be easily inserted into one of the apertures. When the pressure on the eyes is released, the sides of the angle at the vertex or flattened portion 36 tend to expand, whereupon the peg is tightly secured in place.

The game is played in the following manner. Each player selects one of the balls 24, and the segment of the score board corresponding to the ball. One of the players 25 then turns the disk 16 by means of the head 17, and while the disk is in rotation, drops his ball thereon. The ball assumes a more or less irregular course of travel on the rotating disk and finally rolls into one of the depressions 19 when the disk comes to a stop. 30 The player then registers on his score section

the value indicated by the depression into which his ball has rolled. He then removes his ball from the disk and another player performs the operation described. The 35 score is recorded in the manner already indicated, and the player whose peg first reaches the central aperture 33 is declared the winner.

While a specific embodiment of the invention has been illustrated and described, it is to be understood that various alterations in the details of construction may be made without departing from the spirit of 40 the invention as indicated by the appended 45 claim.

Having thus fully described the invention, what I claim as new and desire to protect by Letters Patent is:—

A game comprising a base, a disk rotatably supported thereon, said disk being divided into sectors, a depression and an indicator of the value of said depression in each sector, a plurality of separate objects 50 adapted to be received in said depressions, each object bearing a distinguishing characteristic, and a score board divided into sections each bearing a distinguishing characteristic corresponding to one of said objects. 55

In witness whereof I have hereunto set 60 my hand.

SYDNEY MARTIN.
